PACKING BOX
Floris Meijdam, Laantje Van Van Iperen, Leerdam, Netherlands, assignor to N. V. Vereenigde Glasfabrieken (United Glassworks), Schiedam, Netherlands, a limited-liability company of the Netherlands
Filed Apr. 10, 1961, Ser. No. 101,824
Claims priority, application Netherlands Apr. 8, 1960

The invention relates to a packing box or the like made of corrugated board. Corrugated board has heretofore been considered unsuitable for the outer faces of boxes, which are to have a luxury appearance or which are to be used for windowdressing, for instance, as in the case of boxes for relatively expensive glassware to be displayed in shop windows. The reason is that, even when the outer surface is coloured or covered with paper, whereby the cost of the box is considerably increased, the corrugation is nevertheless visible at the outer surface as a result of the gluing of the interiorly situated corrugated web to the outer sheets of the corrugated board at the ridges or crowns of the corrugations. The box thus has a cheap appearance and such boxes or other containers having outer walls constituted by corrugated cardboard are therefore only considered suitable for inexpensive items or for packages used only during transport from manufacturer to retailer or from store to store.

It is an object of the invention to improve the appearance of boxes, cartons and the like formed of corrugated board without substantially increasing the cost thereof, whereby the field of application of the cheap corrugated cardboard boxes and the like is considerably expanded to encompass the field for which only more expensive luxury boxes, manufactured from smooth material like sheet board, have been previously employed.

In accordance with an aspect of the invention, the locations of the ridges or crowns of the corrugated inner web are masked in a box, carton or the like having corrugated cardboard walls by providing at least the outer flat surfaces of the latter with parallel spaced apart lines, printed or otherwise applied thereto, and extending longitudinally along the ridges or crowns of the underlying corrugated web.

In the case of folding boxes, an attractive effect is further achieved, in that the lines on the folded sides and ends of the box and the cover slidable thereon extend in mutually perpendicular directions, and in that each of the inner sides of the box is embellished by the lines appearing on the inwardly folded flaps. Notwithstanding the above, the lines need only be applied to one side of the corrugated board.

The means whereby the above and further objects to be mentioned hereinafter are obtained will be apparent in the following detailed description of an embodiment of the invention which is to be read in connection with the accompanying drawing wherein:

FIG. 1 is a perspective view of a folding box with a sliding cover to which the invention is applied;

FIGURES 2 and 3 are respectively perspective views of the cover and box separately;

FIGURES 4 and 5 are respectively plan views of flat blanks from which the cover and box are formed; and

FIG. 6 is a fragmentary perspective view of a cut piece of corrugated board which is provided with lines according to the invention.

The several views of the drawing show parallel lines at equal distances from each other on all outer faces, such as, at 17, 24 (FIG. 1) and at 5, 7, 10 (FIG. 2) of a box and of a cover to be slidably placed over the box, with the box and cover being made of corrugated board.

5 The cut piece in FIG. 6 shows that the lines 2 extend in the longitudinal direction of the corrugations of the corrugated web 1 enclosed by the flat cardboard sheets 3 and further that the lines 2 are aligned with the ridges or crowns 4 of the corrugations adhesively secured to the flat sheet 3 forming the outer or visible wall surface.

10 Most surprisingly it has been found that such simple means, e.g. white parallel lines printed on corrugated board, which for the rest has its original colour, give the illusion of an even surface, as a result of which the otherwise always visible corrugations become quite inconspicuous.

15 Colors can now be applied to this corrugated board, without the disturbing effect of the corrugations which was otherwise encountered, so that the total effect can be improved. The boxes manufactured in this way are as attractive in appearance as more expensive boxes made of sheet board.

20 Apart from the fact that the corrugations, which otherwise are outlined against the outer face of the corrugated board giving the latter a cheap appearance, have become invisible, so that the outer faces have the appearance as if they were manufactured from more expensive cardboard, the linear pattern moreover produces an attractive decorative effect.

25 When for instance the linear pattern consists of white lines impressed or printed on coarse, grey or brownish corrugated board, whereby the cost of production remains low, there is nevertheless produced a box with a surprisingly attractive appearance, which does not give at all the impression of a cheap corrugated board package.

30 The drawing shows that the invention is in particular advantageously applied to folding boxes, with only one side of the corrugated board being impressed with the pattern of parallel lines and the latter still being situated on every part of the exterior. In this case, the sides and ends of the box and cover have the lines extending thereon in mutually perpendicular directions. This results in a further improvement of the appearance.

35 40 The folding box with sliding cover which hereinafter will be described in detail presents moreover an embellished interior for the box and cover, even though the linear pattern according to the invention has only been applied to one side of the corrugated board.

45 The blank for the cover (FIG. 4) includes a central plane 5 corresponding with the upper side of the cover in FIGURE 1 and which is defined in the material by means of creasing (dotted lines) so that it is adjoined on two opposite sides by flaps 6 and 7. The latter are 50 each in the middle portion thereof provided with a pair of closely spaced creases 8, 9, respectively. Flaps 10 and 11 are joined to the end edges or remaining sides of the central plane 5 and the height a of these flaps corresponds to the distance of the long sides of the central plane 5 from the creases 8 or 9. The flaps 10 and 11 are, at their opposite ends, joined to tabs 12, 13 and 14, 15, respectively, which are separated from the flaps 6 and 7 by an intersecting line so as to be independently foldable about the creases shown in dotted lines at the ends of the flaps 10 and 11.

55 60 In forming the cover of FIGS. 1 and 2 from the blank of FIG. 4, the flaps 10 and 11 are first erected and the tabs 12 and 13, 14 and 15, respectively, are inwardly folded until they correspond with the longitudinal bounds of the central plane 5. Thereafter the flaps 6 and 7 are 65 erected and folded over the tabs 12, 14 and 13, 15 respectively, by means of the pairs of creases 8 and 9. The cover is now ready and shows on the entire outer side and partially on the inner side a pattern of parallel lines extending in alternating directions.

70 75 The box of FIGS. 1 and 3 is formed in a corresponding way, with the exception that, as is to be seen in the

blank of FIGURE 5, the flaps 16 and 17, which are provided with independently foldable tabs 18, 19 and 20, 21, respectively are not provided on the short side but on the long side of the bottom face 22.

As is apparent in FIG. 3, the over-lay flaps 24 and 25 are positioned at the shorter sides or ends of the box, so that both the inside and the outside of the box have a variation in the directions of the linear patterns, as compared with the patterns on the cover.

A further advantage obtained in this way is that everywhere along the sides of the box there is provided four thicknesses of the corrugated board when the cover is slidably applied on the box. At the ends of the box and cover, the four thicknesses are defined by the doubled over flaps 24 or 25 and the tabs 18 and 19 or 20 and 21, of the box, and by the flap 10 or 11 of the cover. At the sides of the box and cover, the four thicknesses of corrugated board are defined by the flap 16 or 17 of the box and by the doubled over flaps 6 or 7 and the tabs 12 and 14 or 13 and 15. Thus, a fragile article in the 20

What I claim is:

A packing box having walls of corrugated board including outer flat layers and an interior corrugated layer having parallel ridges adhesively joined to said flat layers, and printed impressions of parallel lines at least on the outer surfaces of said walls, said parallel lines on each wall extending longitudinally in the direction of said ridges of the corrugated layer of the related wall and being aligned with said ridges to mask the locations of the adhesive attachment of said ridges to the outer flat layer constituting the outer surface of said related wall.
